UNITED STATES PATENT OFFICE

FRANK RODGERS NEELY, OF ALLENTOWN, PENNSYLVANIA, ASSIGNOR TO A. H. BALLIET CORPORATION, OF ALLENTOWN, PENNSYLVANIA, A CORPORATION OF PENNSYLVANIA

LINING AND HINGE REINFORCEMENT FOR CIGAR BOXES

Application filed November 2, 1927. Serial No. 230,432.

My invention relates to the lining and hinge reinforcement of cigar boxes.

The main purpose of my invention is to simplify and cheapen the lining and hinge reinforcing operations in a cigar box. I accomplish this by using a stronger lining paper than usual and extending the lining paper to cover the inner face of the hinge and serve the additional purpose of hinge reinforcement.

10 A further purpose is to facilitate machine-placing of box hinge reinforcements.

In the drawings I have shown a form of my invention which is inexpensive and thoroughly practicable and which at the same time well illustrates the principles of my invention.

Figure 1 is a perspective view of a cigar box having my lining and hinge reinforcement in position. I have omitted the normal inside label covering the inner face of the lid and extending slightly down into the box.

Figure 2 is a section of Figure 1 taken upon line 2—2.

Figure 3 is a plan view to reduced scale showing a lining and hinge reinforcement blank.

Figure 4 is a section corresponding to Figure 2 but showing a partial lining only in the box.

Figure 5 is a plan view to reduced scale showing a partial lining with hinge reinforcement.

25 In the drawings similar numerals indicate like parts.

The showing of the cigar box in the illustration is intended to be a conventional one showing the usual front 6, back 7, sides 8, bottom 9 and lid 10. As usual, at the front and back the edges are dropped at 11 and 12 as compared with the edges 13 of the sides in order to provide place for the lid.

The customary fabric hinge 14 is shown as 45 attached to the upper edge of the back of the box and to the top and rear edge of the lid.

In the past it has been customary to use in addition an inside hinge reinforcement, 50 glued to the upper inside surface of the back

7 down to some such point as 15, and glued at its upper edge over the upper rear drop edge 12 of the box and over the inner rear face 16 of the lid. This reinforcement has prevented breaking down of the lid of the box 55 in the position shown in Figures 2, 3 and 4 and has more particularly made it possible to safely handle a box by the lid, even when the box is full of cigars.

In this prior practice the paper used for hinge reinforcement was very much stronger and thicker than the paper used for the lining and the paper of the lining overlapped the hinge-reinforcing strip. This meant a 60 double thickness of paper for part of the upper inside face of the back and required two operations for the placing of the lining and hinge reinforcement respectively.

I have found that the lining and hinge reinforcement can be applied either by hand or by machine very much more cheaply and conveniently by a single operation than by two operations and that it is not necessary to use for the purpose a paper as thick and strong as that now ordinarily used for hinge reinforcement. They can be made in a single piece only slightly stronger than the paper now used for the lining.

75 A single piece lining 17 is shown in Figure 1 and a part 17' of a two-piece lining 17' is shown in Figure 4. Whichever form is used this lining glued to the back of the box is extended at 18 so as to be glued to the rear drop edge 12 and to the rear inner face of the lid at 16 to offer the reinforcement.

80 Except for the extension 18 and the stronger paper, the lining can be of any of the types previously used. I have shown conventional forms having the flaps 19 of suitable size and shape to fit the inside faces of the front and back of the box, and the central portions 20, 20' adapted to cover all or a part of the bottom of the box and the end portions 21, if desired, for the insides of the ends of the box.

85 The additional weight of paper adds slightly to the cost, to an amount, however, not nearly approaching the saving in the labor cost in placing the lining and hinge reinforcement.

90 By using a single sheet for the lining and 100

for the hinge reenforcement I am able to secure a better hold of the hinge reenforcement within the back of the box, where this is thought to be desirable, by extending the gluing down further than is usual, without having to provide additional paper, as would be the case with the separate strip. This determines the extent of gluing from the hinge-reenforcement standpoint rather than from that of the slight glue hold required to retain the lining.

My invention requires that the lid shall be attached to the box before the lining is put in place. The invention can be carried out either by hand or machine insertion of the lining and hinge reenforcement.

As compared with machine insertion of the hinge reenforcement alone, the combined lining and reenforcement can be handled very much more easily by a machine than can the much smaller reenforcement alone because the lining can be positioned and supported in a machine and within the box more easily and more accurately than can the separate hinge reenforcement strip.

Because my invention does not interfere with but is supplemental to the normal inside label covering the inner face of the lid and extending over the hinged section and down into the upper part of the box I have not illustrated this label.

It will be seen that my invention shortens and cheapens the operation of lining and hinge reenforcement, permits a longer glue hold of the reenforcing paper within the box without extension of depth of a reenforcing member, and facilitates machine insertion of the hinge reenforcement.

In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention what I claim as new and desire to secure by Letters Patent is:

1. A cigar box having a drop-lid back and a lid in line with the upper edge of the back, a lining member and hinge reenforcement separate from the inside lid label glued to the inside of the back near the top and extending over and glued to the drop-lid edge of the back of the box and the inside rear surface of the lid and of strength sufficient to serve as the inside hinge reenforcement.

2. As an article of manufacture, a paper blank comprising a cigar box lining member and inside hinge reenforcement having one edge extending beyond the lining edge for hinge reenforcement purposes, the strength of the paper and extension being greater than

the normal strength of box linings and sufficient for use in place of the inside hinge reenforcement.

3. A cigar box having a drop-lid back and a lid in line with the upper edge of the back, a hinge strip glued directly to the upper outer face of the back of the box and to the rear edge of the rear outer face of the lid, a lining member and inside hinge reenforcement free from lithographing glued to the inside of the back near the top and extending over and glued to the drop-lid edge of the back of the box and the inside rear surface of the lid and having much greater extension within the box than over the lid.

4. A cigar box having a drop-lid back and a lid in line with the upper edge of the back and a lining member intended to be supplemental to the inside lid label and itself free from lithographic decoration glued to the inside of the back near the top and extending over and glued to the drop-lid edge of the back of the box and the inside rear surface of the lid and taking the place of the normal inside hinge reenforcement.

5. As an article of manufacture, a paper blank comprising a cigar box lining member and inside hinge reenforcement having one edge extending beyond the lining edge for hinge reenforcement purposes, from the box up over the lower inside surface of the lid, the strength of the paper of the lining and extension being sufficient for hinge reenforcement purposes intermediate between the normal strength of box linings and the normal strength of inside hinge reinforcements.

6. A cigar box having a drop-lid back and a lid in line with the upper edge of the back and a lining member for the box glued to the inside of the back of the box near the top, extending over and glued to the drop-lid edge of the back of the box and the inside rear surface of the lid intended to be supplemental to the inside lid label, composed of paper of strength intermediate between the normal strength of box linings and the normal strength of inside hinge reinforcements and having much greater extension within the box than upon the inside surface of the lid.

FRANK RODGERS NEELY.
